UNITED STATES PATENT OFFICE

WILLIAM E. WINE, OF TOLEDO, OHIO

DOOR MECHANISM FOR RAILWAY CARS

Application filed February 5, 1929, Serial No. 337,634. Renewed April 15, 1930.

My invention relates to door mechanism for railway cars and has for its principal object the provision of strong and efficient means for sustaining those lading discharge doors which are movable to open position under the influence of gravity in any desired position of adjustment for regulating or dampening the discharge of lading, such as ballast and the like, from the car.

10 A primary feature of the invention resides in providing portions of the door supporting mechanism carried by the car body and door respectively, with means for cooperating with a chain device adapted to sustain the door in any desired position of adjustment after the latter has been released from its supporting hook for regulating the discharge of lading from the car, the chain cooperating portions of the door supporting mechanism being arranged so that the chain will be disposed substantially parallel to a line tangent to the arc described by the free edge of the door upon initial opening movement of the latter.

25 Another feature of the invention consists in fashioning that member of the door supporting mechanism carried by the car body which overlies the outer face of the hook with a downwardly projecting extension, the extension and a portion of the arm carried by the door being cooperable with a chain for sustaining the door in any desired position of adjustment, after the latter has been released from the door supporting hook, for regulating the discharge of lading from the car.

Other and more specific features of the invention residing in advantageous forms and relations of parts will hereinafter appear and be pointed out in the claims.

40 In the drawings illustrating a preferred embodiment of the invention:

Figure 1 is a fragmentary side view of a car hopper and its associated door illustrating the invention applied thereto.

Figure 2 is a fragmentary sectional view on line 2—2, Figure 1, a portion of the door supporting hook being omitted.

50 Figure 3 is an enlarged detailed view illustrating the manner in which the hook

end of the chain cooperates with the various links of the latter.

Figure 4 is a fragmentary view taken on line 4—4, Figure 3.

Figure 5 is a detailed sectional view taken on line 5—5, Figure 1.

While the drawings illustrate a single hopper and the adjacent edge of its coacting door, it is understood that this construction is duplicated on the opposite side of the car and that the door shown is but one of the door sections which are disposed on opposite sides of the car center sill and which are connected by a spreader or stiffening member so as to swing as one.

In the drawings 1 indicates the hopper side sheet and 2 the bottom or slope sheet thereof. The outer edges of these sheets define the lading discharge opening of the hopper and the portions thereof adjacent the latter are preferably reinforced by a suitably shaped bar or plate 3. The hopper discharge opening is normally closed by a sheet metal door 4 hingedly connected to the car body in any convenient manner (not shown) so as to swing to open position under the influence of gravity.

Mounted upon the outer face of the door is a spreader or stiffener 5 which, in addition to reinforcing the door, serves to tie together the door sections, of which the door 4 is one, to cause them to swing as a unit. The spreader may be advantageously formed with two flanges 6 and 7, respectively, the flange 6 lying against and secured to the outer face of the door by rivets 8 and the flange 7 projecting outwardly from the door substantially normal thereto. The outer end of the stiffener which projects beyond the side edge of the door constitutes an arm and the flange 6 thereof affords means for cooperating with the door supporting mechanism carried by the hopper.

Pivottally mounted on the side sheet of the hopper is a hook 9 of usual design having a plurality of ledges 10 engageable with the flange 6 of the spreader for supporting the door in partially and in fully closed position. Overlying the outer face of the hook and secured to the hopper side sheet is a bracket

or cover plate 11 having a plate portion 12, the bracket being secured to the hopper in a manner such that the plate portion thereof lies in a plane substantially parallel with the adjacent hopper side sheet. The inner face of the cover plate is provided with a plurality of inwardly projecting lugs or bosses 13 apertured to receive attaching rivets 14. The inner end of the foremost boss 13, bears 10 against the reinforcing member 3 while the inner ends of the other bosses cooperate with ferrules or washers 15, all of these parts being arranged so as to space the cover plate a sufficient distance outwardly of the hopper side sheet to permit free pivotal movement of the hook. In addition to this, one of the bosses 13 serves as a pivotal support for the hook 9. Pivotedly mounted on the bracket in a manner similar to that of the hook is a cam 16 adapted to cooperate with the upper edge of the latter for locking the hook in door supporting position to prevent accidental opening movement of the door. The outer face of the cover plate is fashioned 20 with a laterally projecting apertured lug 17 for cooperating with a removable prying lever which may be employed for obtaining a mechanical advantage to force the door from partially to fully closed position.

25 Operatively interposed between the hopper and its coating door is a detachable chain device 18 adapted to arrest opening movement of the door, after it has been released from its supporting hook, to sustain the door in any desired position of adjustment for regulating or controlling the discharge of lading from the door. The lower portion of the cover plate is fashioned with a downwardly projecting extension 19 having an aperture 20 and the outer end of the flange 7 of the door arm is also apertured 30 as at 21 for respectively receiving the chain.

35 The chain device employed comprises a plurality of relatively small links 23 and a hook member 24 attached to one of the end links of the chain. When it is desired to use the car in a service necessitating controlling or regulating the discharge of lading from the car, the chain is threaded through apertures in the cover plate and door arm, after the door is supported in closed position by the hook 9, and the opposite ends of the chain may then be connected, by the hook 24 thereof engaging one of the chain links, to prevent the chain from dragging along the roadway and from being lost. The portion of the cover plate 11 adjacent the lower edge of the aperture 20 is bent or flared outwardly, as indicated at 22, so that the chain may 40 readily pass between the inner face of the cover plate 11 and the adjacent portion of the hopper side sheet when it is being threaded through the aperture 20.

45 The hook 24 is so designed and proportioned that any one of the links of the chain

may be inserted edgewise into the hooked end of the member 24, longitudinal movement of the engaged link being prevented by the portions of the two adjacent links respectively engaging the opposite side edges of the hook. Thus it will be readily appreciated that the door may be maintained in any one of a plurality of positions of adjustment for regulating the discharge of lading from the car.

70 The chain cooperating portions of the door arm 5 and of the cover plate 11 are so arranged that when the chain is in operative position it will be disposed substantially parallel to a line tangent to the arc described by the edge of the door upon initial movement thereof, or in other words, they are arranged at equal radial distances from the hinge axis of the door. This relative disposition of these portions enables a finer degree of adjustment of the door to be obtained than would otherwise be the case. A fine degree of adjustment is also obtained by constructing the chain so that when in use it, in effect, 80 forms an endless chain as it will be appreciated that the distance between one position of adjustment of the door to the next one measured along the arc described by that portion of the door adjacent the chain is one 85 half the distance between the centers of each 90 link.

95 From the foregoing it is thought that the operation will be apparent. Prior to releasing the door from supporting engagement with the hook 9, the hook 24 of the chain is engaged with that link of the chain which will permit the door to open to the desired degree. The hook 9 is then moved to inoperative position and opening movement of the door is arrested by the chain and it is sustained in the position of adjustment theretofore determined.

100 I claim:

1. In a door mechanism for railway cars, the combination with a hinged door movable to open position under the influence of gravity, of a hook member pivotally mounted on the car body and cooperable with the door for supporting it in closed position, a bracket having a plate portion overlying the outer face of the hook and disposed in a plane substantially parallel with adjacent portions of the car, the plate portion of said bracket being provided with an aperture, a member mounted upon the door, and a chain device 110 cooperable with the latter and the apertured portion of said bracket adapted, upon release of the door from its supporting hook, to arrest opening movement of the door to sustain it in a desired position of adjustment for regulating the discharge of lading from the car.

115 2. In a door mechanism for railway cars, the combination with a hinged door movable to open position under the influence of gravity, of a hook member pivotally mounted on 120

the car body for cooperating with the door to support it in closed position, a cover plate overlying the outer face of the hook and having a downwardly projecting extension, a member mounted on the door, and a chain device cooperable with the latter and said cover plate extension for arresting opening movement of the door upon its release from the hook to sustain it in a desired position of adjustment for regulating the discharge of lading from the car.

3. In a door mechanism for railway cars, the combination with a hinged door movable to open position under the influence of gravity, of a hook member mounted on the car body for cooperating with the door to support it in closed position, a cover plate overlying the outer face of the hook and having a downwardly projecting apertured extension, the portion of the plate adjacent the lower edge of said aperture being flared outwardly from the adjacent portion of the car, a member mounted on the door, and an endless chain passing through said aperture and cooperable with said member for arresting opening movement of the door upon it being released from the supporting hook for sustaining it in any desired position of adjustment for regulating the discharge of lading from the car.

4. In a door mechanism for railway cars, the combination with a hinged door movable to open position under the influence of gravity, of a hook member mounted on the car body for cooperating with the door to support it in closed position, a bracket having a plate portion overlying the outer face of the hook and disposed substantially parallel to adjacent portions of the car, a member mounted on the door, and a chain device cooperable with the latter and a portion of said bracket for arresting opening movement of the door upon its release from the supporting hook to sustain it in a desired position of adjustment for regulating the discharge of lading from the car, the chain cooperating portions of the bracket and door member being arranged so that the chain will be disposed substantially parallel to a line tangent to the arc described by the free edge of the door upon initial opening movement of the latter.

5. In a door mechanism for railway cars, the combination with a hinged door movable to open position under the influence of gravity, of a hook member mounted on the car body for cooperating with the door to support it in closed position, a cover plate overlying the outer face of the hook and having a downwardly projecting extension, a member secured to the door, and a chain having operative connection with said member and said cover plate extension for arresting opening movement of the door upon its release from the supporting hook to sustain it in a desired position of adjustment for regulating the discharge of lading from the

car, said chain when in operative position being substantially normal to the door in all positions in which the door may be supported.

6. In a door mechanism for railway cars, the combination with a hinged door movable to open position under the influence of gravity, of a hooked member mounted on the car body for cooperating with the door to support it in closed position, a cover plate overlying the outer face of the hook and having a downwardly projecting extension, an arm secured to the door provided with a plurality of flanges, one of said flanges being apertured, and a chain cooperable with the apertured portion of the door arm and the cover plate extension, one end of said chain having a hook adapted to cooperate with any one of a plurality of links of the chain adjacent the opposite end thereof to maintain the door in a desired position of adjustment after it has been released from the supporting hook to regulate the discharge of lading from the car.

7. A cover plate member for car door mechanism of the type involving a hook device pivotally mounted on the car body and adapted to cooperate with a hinged door to support the latter against opening movement, said member being adapted to be secured to the car body in overlapping relation to the outer face of the hook, said cover plate being provided with a plurality of apertures, one of said apertures being adapted to cooperate with a removable door prying lever, and the other of said apertures being adapted to cooperate with means for retaining the door in a plurality of positions of adjustment after the latter has been released from its supporting hook for regulating the discharge of lading from the car.

8. A cover plate member for car door mechanism of the type involving a hook device pivotally mounted on the car body and adapted to cooperate with a hinged door to support it against an opening movement, said member being adapted to be secured to the car body in overlapping relation to the outer face of the hook device and being provided with a laterally extending lug and a downwardly projecting extension, said lug forming a fulcrum for a removable door prying lever and said extension being cooperable with means to sustain the door in a plurality of positions of adjustment after the latter has been released from the door supporting hook to regulate the discharge of lading from the car.

In testimony whereof I affix my signature.
WILLIAM E. WINE.
